BUCKLE

Paul W. White, New Haven, Conn., assignor to Parva Products Company, Chicago, Ill., a corporation of Delaware

Application August 26, 1952, Serial No. 306,459

3 Claims. (Cl. 24—194)

The present invention relates to shoe buckles, more particularly to slide-type shoe buckles adapted to be mounted on shoe straps, and the invention has for an object the provision of a slide-type shoe buckle which may readily be stamped from sheet metal, is of rugged construction, and is inexpensive to manufacture and which is effective to clamp firmly or release readily the shoe-strap to which the buckle is attached.

Specifically, the present invention relates to improvements in shoe buckles of the type disclosed and claimed in my prior Patent No. 2,599,031, issued June 3, 1952, whereby the clamping action of the buckle is substantially increased while at the same time permitting a very fine adjustment of the buckle by the wearer while the buckle is being worn and while maintaining tension on the buckle strap.

Briefly, in accordance with one aspect of the invention, the slide buckle comprises a frame and slide having side bars and crossbars defining strap receiving openings therein to receive a strap, the frame sidebars having side walls extending rearwardly of the face of the frame and inturned slide supporting shoulders to support the slide. One of the frame crossbars is provided with a rearwardly extending upwardly inclined tongue portion of substantially less width than the strap receiving opening in the frame, and the end of this tongue portion is turned under to define an inclined strap-engaging portion adapted to engage the central portion of a strap threaded through the frame and slide openings. One of the slide crossbars is provided with a strap clamping portion extending upwardly out of the plane of the slide to retain the slide within the frame for sliding movement along said shoulders, this strap clamping portion cooperating with the inturned end portion of the frame crossbar to clamp therebetween the strap threaded through said openings. With this arrangement the top edge portions of the strap are snubbed around the corners of the strap-engaging portion of the frame crossbar when tension is applied to the strap so that an effective clamping action is obtained.

In accordance with a further aspect of the invention, the other slide crossbar is positioned in the plane of the slide and spaced from the strap clamping slide crossbar so that the front edge of this other slide crossbar projects beyond the front edge of the frame crossbar when a strap is clamped between the frame and slide crossbars. Accordingly, a very fine adjustment of the strap may be made by the wearer while the buckle is being worn and while tension is maintained on the strap by simply exerting a slight pressure upon the projecting front edge of the forward slide crossbar. Furthermore, this adjustment is permitted while maintaining the snubbing action around the corners of the strap-engaging portion of the frame crossbar.

For a more complete understanding of the invention, reference should now be had to the drawings, in which:

Fig. 1 is a top plan view of an assembled buckle embodying the features of the present invention shown at

tached to the end of a strap and with the slide withdrawn;

Fig. 2 is a bottom view partly in section of the buckle and strap of Fig. 1 shown with the slide in forward position;

5 Fig. 3 is a front elevational view of the buckle of Fig. 1;

Fig. 4 is a righthand side view of the buckle of Fig. 3 taken along the line 4—4 of Fig. 3;

10 Fig. 5 is a sectional view taken along the line 5—5 of Fig. 10;

Fig. 6 is a top plan view of the buckle frame;

Fig. 7 is a top plan view of the buckle slide;

Fig. 8 is a side elevational view of the buckle slide;

15 Fig. 9 is a longitudinal sectional view showing the frame and slide in assembled position with a strap partially threaded therethrough;

Fig. 10 is a sectional view similar to that of Fig. 9 but showing the buckle and strap in clamping relation;

20 Fig. 11 is a top plan view of an alternative form of buckle applied to a shoe strap; and

Fig. 12 is a longitudinal sectional view of the buckle of Fig. 11 showing the buckle and strap in clamping relation.

Referring now to the drawings, the invention is shown 25 as comprising a shoe buckle including a sheet metal frame 10 (Fig. 6), which may be conveniently and economically formed by a simple stamping operation, and a sheet metal slide 11 (Figs. 7 and 8), which may be formed by a similar stamping operation and which is adapted to

30 cooperate with the frame 10. As shown, the frame 10 comprises a pair of sidebars 12 and 13 and a pair of crossbars 14 and 15, which together form a suitable strap receiving opening 17 through which a strap may be threaded. The frame 10 is also provided with sidebar

35 extensions 18 and 19, the rear portions of which are inclined upwardly from the main plane of the frame 10, a third crossbar 20 which is employed as a strap attaching bar for attachment of the strap to the buckle frame 10, and an end crossbar 21 which may be employed as a

40 strap hold-down bar, as best shown in Fig. 10. With the sidebar extensions 18 and 19 inclined upwardly sufficient space is provided to permit the insertion of the strap under the hold-down bar 21 when the buckle is worn on the side of the shoe. In this connection, it will be understood that if the buckle is worn on the front of the shoe the sidebar extensions 18 and 19 may be substantially coplanar with the main plane of the frame 10 since the curvature of the ankle gives sufficient additional space to permit insertion of the strap under the hold-down

50 bar 21.

As best shown in Fig. 2, the sidebars 12 and 13 are provided with rearwardly extending side wall portions 22 and 23 which form a recess suitable for receiving the slide 11. The side portions 22 and 23 are provided adjacent

55 the forward ends thereof with inwardly extending shoulder portions 24 and 25 which extend along the sidebars 12 and 13 and rearwardly of the face of the buckle to provide slide-supporting runners or shoulders adjacent the strap receiving opening 17. The strap attaching bar

60 20 of the frame 10 is provided with an intermediate portion which is depressed relative to the upper face of the buckle frame so that when the end of the strap is secured to the bar 20 by means of thread or the like, the thread is confined to the intermediate portion of the bar

65 20 and cannot ride up along the inclined end portions thereof, thereby preventing the slide from striking the strap-securing thread and cutting the same, as described in detail in my prior Patent No. 2,599,031 identified above.

70 The forward crossbar 14 of the frame 10 is provided with a rearwardly extending, upwardly inclined tongue portion 26 which projects rearwardly over the strap re-

ceiving opening 17 in the frame 10 and is provided with an end portion 27 of substantially less width than the strap receiving opening 17 which is turned under the inclined portion 26 to provide an inclined strap-engaging portion 27 adapted to engage the central portion of the strap threaded through the opening 17. Accordingly, the corners 28 and 29 formed by turning under the portion 27, are positioned well within the strap receiving opening 17 so as to permit the edge portions of the strap to be snubbed around these corners when tension is applied to the strap, as will be described in more detail hereinafter.

Referring now to Figs. 7 and 8, the slide 11 comprises a pair of crossbars 30 and 31 which are connected by suitable sidebars 32 and 33 to define a strap receiving opening 34. The crossbar 31 is deformed slightly downwardly to position this bar slightly below the main plane of the slide 11 and the crossbar 31 is provided with an upwardly extending strap clamping portion 35 which extends upwardly out of the main plane of the slide 11. The strap clamping portion 35 also serves as a stop to limit the travel of the slide 11 within the frame 10. Thus, the strap clamping portion 35 strikes the crossbar 15 of the frame 10 to limit the travel of the slide 11 in the rearward direction, and the portion 35 strikes the crossbar 14 to limit travel of the slide 11 in the forward direction when the buckle is unthreaded.

In order to assemble the slide 11 in the frame 10, the slide 11 is inserted into the frame and the slide supporting shoulders 24 and 25 are thereafter deformed inwardly to the position shown in the drawing, thereby permanently retaining the slide 11 within the frame 10.

Once the slide and frame have been assembled together in the manner described above, the operation of the buckle thereby produced is in general similar to the operation set forth in my prior patent identified above, but by reason of the correlation and proportioning of the parts in the present buckle, an increased clamping action is provided while at the same time permitting a microscopic adjustment of the buckle by the wearer while tension is maintained on the strap. The strap receiving openings 34 and 17 in the slide and frame, respectively, are in alignment to permit threading of a strap there-through as shown in Fig. 9. The crossbar 30 constitutes the pull-up bar of the buckle and the strap clamping portion 35 of the crossbar 31 constitutes the clamping bar of the buckle. The portion 35 in cooperation with the strap-engaging portion 27 of the crossbar 14 of the frame 10 serves to clamp the strap in adjusted positions in the buckle whenever tension is applied to the strap.

In Figs. 1 to 5, inclusive, 9 and 10, the buckle is shown in conjunction with a strap comprising an end portion 36 which is secured to the depressed central portion of the strap attaching crossbar 20 by means of the thread 37. The free end portion 38 of the strap is adapted to be threaded through the strap receiving openings in the frame 10 and slide 11 and adjustably clamped in the buckle. In Fig. 9, the buckle is shown with the frame 10 and slide 11 in strap-threading position with the free end 38 of the strap extending through the strap-receiving openings 34 and 17. When tension is applied to the strap, engagement of the strap portion 38 with the pull-up crossbar 30 on the slide will cause the slide to move in a lefthand direction from the position shown in Fig. 9 to the position shown in Fig. 10, in which latter position the strap is firmly clamped between the upstanding portion 35 of the crossbar 31 on the slide 11 and the inclined strap-engaging portion 27 of the forward crossbar 14 on the frame 10. Thereafter, the loose end of the strap portion 38 may be inserted beneath the hold-down bar 21 as shown in Fig. 10.

It will be noted that the top edge portions 38a and 38b of the free end 38 of the strap are snubbed around the corners 28 and 29 defined by the turned under strap engaging portion 27 on the frame 10 when tension is

5 applied to the strap as is best shown in Figs. 5 and 10. This snubbing action is provided by making the turned under portion 27 of substantially less width than the strap which is threaded through the strap-receiving openings in the buckle so that the edge portions of the strap may curl upwardly around the edges of the portion 27 when tension is applied to the strap. This snubbing action is also increased by so positioning the forward crossbar 30 of the slide 11 relative to the clamping portion 35 that the crossbar 30 is adjacent the forward portion of the crossbar 14 on the frame 10 when the strap is clamped so that the strap is positioned generally parallel to the inclined portion 27 thus permitting the edge portions 38a and 38b of the strap to be snubbed around the corners of the portion 27 as described above.

10 In order to provide for microscopic adjustments of the buckle while it is being worn and while maintaining the above described clamping action, so that the buckle, once adjusted, stays in its adjusted position, the pull-up crossbar 30 of the slide 11 is so positioned that it projects beyond the front edge of the crossbar 14 on the frame 10 when the strap is clamped in the buckle, as clearly illustrated in Fig. 10. With this arrangement of the parts, the buckle may be readily and conveniently adjusted by 15 the wearer by exerting a slight pressure on the protruding portion of the slide crossbar 30. Furthermore, this adjustment can be made without taking the loose end of the strap from beneath the hold-down 21 of the buckle. Thus, if the adjustment of the buckle is too tight, the wearer's finger may be placed against the protruding edge of the crossbar 30 and the slide moved rearwardly slightly so that the strap is adjusted by a very small amount, in the order of $\frac{1}{32}$ of an inch or less. Furthermore, the adjustment may be made even finer by simply giving a slight lifting action to the forward end of the buckle so that the adjustment of the buckle may be varied by an extremely small amount to loosen the strap very slightly. It will also be noted that the above described adjustments can be made while maintaining the same clamping position on the strap so that once the adjustment is made the clamping and snubbing action described above is immediately obtained.

20 Whenever it is desired to remove the strap from the buckle the free end of the strap is removed from under the hold-down bar 21 and a slight pull is exerted on the free end of the strap in the righthand direction as viewed in Fig. 10 so that the slide 11 is moved toward the threading or releasing position shown in Fig. 9.

25 It will be observed that the relatively wide pull-up crossbar 30 of the slide 11 has the effect of preventing the insertion of the free end of the strap 38 between the frame crossbar 14 and the crossbar 30. By reason of this construction there is very little possibility of threading the free end of the strap into the buckle incorrectly since it can be readily inserted only through the strap receiving openings 34 and 17.

30 In Figs. 11 and 12 there is shown an alternative embodiment of the present invention. In this alternative embodiment the buckle frame 50 is substantially identical to the buckle frame 10 described in detail above. However, the buckle slide 51 of the embodiment shown in Figs. 11 and 12 is modified so as to prevent the slide from cutting into the strap when an extremely heavy pressure is applied thereto. Thus, the slide 51 is provided with a rear crossbar 52 having an upwardly extending strap clamping portion 53 which is inclined forwardly at an angle of approximately 45 degrees as clearly shown in Fig. 12. The strap clamping portion 53 is provided with a turned under portion 54 so that a smooth round edge 55 of relatively large radius engages the underside of the strap 38. With this arrangement, the strap clamping portion of the crossbar 52 is prevented from cutting into the strap 38 when extremely heavy tension is applied thereto since the round edge 55 provided by turning under the portion 54 provides a smooth surface 35 for engagement with the strap. By inclining the strap

clamping portion 53 forwardly, the clamping action of the buckle is also increased.

While particular embodiments of the invention have been shown, it will be understood, of course, that the invention is not limited thereto since many other modifications may be made and it is therefore contemplated by the appended claims to cover any such modifications as fall within the true spirit and scope of the invention.

What is claimed as new and desired to be secured by Letters Patent of the United States is:

1. A slide buckle comprising, a frame, a slide for cooperation with said frame, said frame and said slide having side-bars and cross-bars defining strap receiving openings therein to receive a strap, said frame side bars having side walls extending rearwardly of the face of said frame and inturned slide supporting shoulders, one of said frame cross-bars having a rearwardly extending upwardly inclined tongue portion extending over the strap receiving opening in said frame and provided with an end portion of substantially less width than the strap receiving opening which is turned under said tongue portion adjacent said opening, one of said slide cross-bars having a strap engaging portion of a width substantially less than the width of said strap receiving opening in said frame and adapted to limit movement of said slide along said shoulders in both directions, said strap engaging portion extending upwardly out of the plane of said slide for cooperation with end portion to clamp therebetween a strap threaded through said openings, the other of said slide cross-bars being positioned in the plane of said slide and spaced from said one slide cross-bar so that the front edge of said other slide cross-bar projects beyond the front edge of said one frame cross-bar when a strap is clamped between said one frame and slide cross-bars, whereby said slide may be moved rearwardly to permit fine adjustment of the strap while maintaining tension thereon.

2. A slide buckle comprising, a frame, a slide for cooperation with said frame, said frame and said slide having side-bars and cross-bars defining strap receiving openings therein to receive a strap, said frame side bars having side walls extending rearwardly of the face of said frame and inturned slide supporting shoulders, one of said frame cross-bars having a rearwardly extending, upwardly inclined tongue portion of substantially less width than the strap receiving opening in said frame, said tongue portion projecting rearwardly over the strap receiving opening in said frame and having the end portion thereof turned under to define an inclined strap engaging portion adapted to engage the central portion of a strap threaded through said openings, one of said slide cross-bars having

45
50

a strap clamping portion of a width substantially less than the width of said strap receiving opening in said frame and adapted to limit movement of said slide along said shoulders in both directions, said strap clamping portion extending upwardly out of the plane of said slide, said strap clamping portion cooperating with said strap engaging portion to clamp therebetween a strap threaded through said openings, the top edge portions of the strap being snubbed around the corners of said strap engaging portion when tension is applied to the strap.

3. A slide buckle comprising, a frame, a slide for cooperation with said frame, said frame and said slide having side-bars and cross-bars defining strap receiving openings therein to receive a strap, said frame side bars having side walls extending rearwardly of the face of said frame and inturned slide supporting shoulders, one of said frame cross-bars having a rearwardly extending, upwardly inclined tongue portion of substantially less width than the strap receiving opening in said frame, said tongue portion projecting rearwardly over the strap receiving opening in said frame and having the end portion thereof turned under to define an inclined strap engaging portion adapted to engage the central portion of a strap threaded through said openings, one of said slide cross-bars having a strap 15
